Primary Examiner — Richard Kearney*Assistant Examiner* — Landon Thomas Cassell(74) *Attorney, Agent, or Firm* — Pryor Cashman LLP(57) **CLAIM**

The ornamental design for a strain relief, as shown and described.

DESCRIPTION

FIG. 1 is a front left perspective view of a strain relief in accordance with the present invention;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines illustrate environmental subject matter that forms no part of the claimed design.

1 Claim, 4 Drawing Sheets(56)
